UNITED STATES PATENT OFFICE.

JOHN J. CATRON, OF BONHAM, TEXAS.

MAGAZINE-RIFLE.

No. 920,912.

Specification of Letters Patent. Patented May 11, 1909.

Application filed May 7, 1908. Serial No. 431,420.

To all whom it may concern:

Be it known that I, JOHN J. CATRON, citizen of the United States, residing at Bonham, in the county of Fannin and State of Texas, have invented new and useful Improvements in Magazine-Rifles, of which the following is a specification.

My present invention has relation to magazine rifles, and is designed more particularly as an improvement upon the magazine rifle constituting the subject of my Letters-Patent No. 882,625, dated March 24, 1908.

One of the objects of my present invention is the provision of a magazine rifle embodying simple, reliable and durable means for preventing movement of the trigger and release of the hammer to fire the rifle until after the breech block is securely locked in its closed position.

Another object is the provision in a magazine rifle, of a cartridge elevator adapted to eject each fired shell, except the last, through the medium of means carried by the said elevator for ejecting the last fired shell.

Another object is the provision of a combined breech block and cartridge carrier provided with means for holding the flanged ends of cartridges, means for locking the breech block and cartridge carrier in its closed position, means for opening the cartridge holding means on the closing of the block, and means for releasing the rear-most cartridge in the magazine tube at the same time that the block is locked closed so as to enable the flanged end of the cartridge to assume a position in the cartridge holding means.

Other advantageous characteristics of the invention will be fully understood from the following description and claims when the same are read in connection with the drawings, accompanying and forming part of this specification, in which:

Figure 1 is a view, partly in longitudinal section and partly in elevation, of so much of a magazine rifle as is necessary to illustrate the preferred embodiment of my present invention; the rifle being shown as it appears with the right-hand side plate of its breech frame or housing removed; and with its combined breech block and cartridge carrier locked in its closed position.

Fig. 2 is a similar view with the breech block in its rear or open position. Fig. 3 is a detail longitudinal section taken in a

plane parallel to that of Fig. 2. Fig. 4 is an enlarged detail section taken on line 4-4 of Fig. 2 looking forward. Fig. 5 is an enlarged elevation showing the front end of the rear section of the breech frame and the parts carried by said section. Fig. 6 is an enlarged elevation showing the rear end of the front section of the breech frame and the parts carried by said section. Figs. 7 and 8 are detail views showing the breech block and the vertically swinging locking piece carried thereby. Fig. 9 is an enlarged view, partly in elevation and partly in section, showing the cartridge elevator and the last-shell ejector carried thereby. Fig. 10 is an enlarged section taken on line 10-10 of Fig. 9, looking forward. Fig. 11 is a perspective view showing the combined breech block and cartridge carrier with its cover plate and the connecting screw thereof removed. Fig. 12 is a front elevation of the same. Fig. 13 is a perspective view of the vertically swinging piece for normally retaining the cartridges in the magazine tube. Fig. 14 is an enlarged elevation showing the breech frame with the breech block and the cartridge elevator removed. Fig. 15 is an enlarged, detail perspective view of the plunger for coöoperating with the catch on the trigger.

Similar letters and numerals designate corresponding parts in all of the views of the drawings, referring to which:

A is the barrel of the rifle, and B is the breech frame which may be of the construction disclosed in my aforesaid Letters-Patent or of any other construction consonant with the purposes of the present invention. Fixed at the under side of the barrel and communicating with the forward end of the chamber in the breech frame is a magazine tube C provided with the usual or any other suitable means for pressing the cartridges rearwardly, and on the said tube C is mounted and guided a reciprocatory hand-piece D, to which is fixedly connected the longitudinal bar E for translating the combined breech block and cartridge carrier, presently explained. The forward wall of the chamber in the breech frame is provided at opposite sides of the barrel A and magazine tube C with upright recesses a and a rearwardly-extending, beveled protuberance b, and in said wall is an opening c for the passage of the translating bar E.

F is a vertically-swinging, spring-pressed

piece which normally rests in the position shown in Fig. 3 to prevent the rearmost cartridge being forced from the magazine tube C. Said piece F has a lateral arm d for the engagement of the inclined shoulder e at the lower edge of the bar E, and hence it will be apparent that the piece F will be depressed by the bar E to release the rearmost cartridge from the magazine tube at the same time that the combined breech block and cartridge carrier is locked in its closed position, as hereinafter set forth.

The present embodiment of my invention is one of the "take-down" type common to my aforesaid patent, and G in Fig. 5 is the rear section of the breech frame C, and H in Fig. 6, the front section. The rear section G carries the usual or any other suitable hammer I, and a trigger J which is designed to engage the hammer in the ordinary manner and has a shouldered catch K and a finger L; the said catch and finger lying in parallel, vertical planes, and the finger extending forward of the catch for a purpose hereinafter stated. The combined breech block and cartridge carrier M is carried by the front section H, as is also the bar E for translating the block. In the frame section H a longitudinally-disposed plunger N is guided and held against too free movement, which plunger is provided, at the rear end thereof, with a head P. This head P is, near the end of the rear stroke of the bar E and block M, engaged by a shoulder f of said bar and moved a slight distance rearward under the shoulder of the catch K. The said head P remains in said position during the subsequent forward stroke of the bar E and block M and hence prevents forward movement of the catch K and release of the hammer from the trigger, with the result that there is no danger of the firearm being accidentally fired until the block M is locked in its closed position. During the end portion of the forward movement of the bar E and as the block M is locked in its closed position, by means hereinafter described, a head g on a rearward extension h of the said bar moves the head P a slight distance forward and out of engagement with catch K and thereby releases the trigger so that the firearm can be fired. The finger L of the trigger extends forward of the catch K, as before described, so as to be engaged by the rear end of the block M when the operator's finger is on the trigger and the bar E and block M are rapidly reciprocated as in rapid firing, the block M in that case serving to press the trigger back into engagement with the hammer when the hammer is pressed back by the block.

R is the cartridge elevator, pivoted at i in the breech frame.

The combined breech block and cartridge carrier M is provided on its forward end ad-

jacent to one side with an upright, inwardly-directed beveled flange i². The opposite side of the block M is recessed at j and in said recess is arranged a resilient plate k, fixedly connected at its rear end to the block and provided at its forward end with an inwardly-directed, beveled flange l. The resilient plate k is covered by a plate m¹, connected to the block by a screw n which extends loosely through the plate k. The plate m¹ serves to cover the recess in which plate k is arranged and to protect said plate k. The block M is horizontally notched below the flanges i² and l, as indicated by m, and is also provided at intervals in its height, between said flanges, with horizontal notches m². Carried in said block is a spring-cushioned firing pin S which is recessed in one side at p, Fig. 7. The block M has in its lower side and forward end a slot r for the play of the cartridge elevator R which latter comprises a rear, upwardly-extending arm s and a forward and comparatively long arm t having a lip u at its forward end. From a point slightly below the horizontal notch m the forward end of the slot r is of decreased width—i. e., too narrow for the passage therethrough of the lip u, up to a point v immediately below the firing pin where it is of the same width as at its lower end. On the rear movement of the block M it cooperates with the rear arm of the cartridge elevator to cause the forward arm thereof to rise quickly to the position where the lip u can pass through the portion v of the slot r on the following forward movement of the block. As soon as the lip u passes through said portion v the remainder of the slot r permits the lip u to move to the position shown by dotted lines in Fig. 1; the forward movement of the block M serving to depress the forward arm of the cartridge elevator to said position.

Should the operator attempt a reversal of the forward movement of the block M before the cartridge that is being raised is high enough to enter the barrel A, one of the described notches m or m² will engage the lip u and thereby prevent such reversal of the action.

A flat spring T lies against the side of the cartridge elevator R to prevent too free swinging movement of said elevator.

The cartridge elevator R is provided at its forward end with a shoulder w on which the flanged ends of the cartridges rest during the elevation thereof between the flanges on the forward end of the block M, and at this point it will be understood that each cartridge as it is elevated to a position in line with the barrel A serves to eject the fired shell above it. Now in order to enable the elevator R of itself to eject the fired shell of the last cartridge in the rifle, I pro-

vide the elevator R with the spring-backed ejector U. This latter normally rests above the shoulder w, as shown in Fig. 9, and when the block M is moved rearward and the forward arm of the elevator is raised to raise a cartridge between the flanges on the forward end of the block, the cartridge will hold the ejector U back of the shoulder w. When, however, the forward arm of the elevator is raised without a cartridge thereon, as when the last cartridge in the rifle has been fired, it will be manifest that the ejector U will rest in the position shown in Fig. 9, relative to the elevator R, so that when the forward arm of the elevator is raised to the full extent, the ejector U will extend as high as the firing pin and hence will strike upward against and eject the shell of the said last cartridge.

Pivoted at 1 to the block M is a vertically-swinging piece 2, having a lateral stud 3, disposed in a slot 4 of the translating bar E, whereby the said block M derives rectilinear movement from the bar. The lower corner of the swinging piece 2 is designed to coöperate with a depression 5 in the breech frame to lock the block M in its closed position, and it will be readily understood that when the hammer is cocked or half cocked while the block M is in its closed position, the firing pin is pushed rearward by its spring so that its portion in front of its recess p rests above the piece 2 and holds the latter against upward movement. When, however, the hammer acts against the rear end of the firing pin to force the pin forward and fire the rifle, the recess in the firing pin assumes a position above the upwardly-directed arm of the piece 2 and consequently said piece 2 is free to move upward to unlock the block M from the breech frame. It will also be understood that when the bar E is moved forward to carry the block M to its closed position, the slot 4 in the bar coöperates with the stud 3 on piece 2 to draw the arm of the latter down out of the recess in the firing pin, and to seat the piece 2 in the depression 5 of the breech frame so as to lock the block M in its closed position. This action takes place during the end portion of the forward movement of the bar E and the block M, and at the same time the shoulder e of bar E engages the arm d of the vertically swinging piece F and by depressing the same permits the rearmost cartridge in the magazine tube to fly back so that its flanged end rests between the inwardly directed flanges on the forward end of the block M.

It will be understood at this point that as the block M approaches its closed position, the beveled flange 7 on its resilient plate will engage the beveled protuberance b on the forward wall of the chamber in the breech frame so that when the block is

locked closed, the flange 7 will be sprung outward to freely receive the flanged end of the rearmost cartridge between it and the other flange on the block. Then when the block is drawn rearward the cartridge 70 because of the spring-backed follower in the tube C will closely follow the block until the flange 7 passes out of engagement with protuberance b when said flange 7 will spring inward and hold the flanged end of 75 the cartridge between it and the other flange, and the cartridge will be carried rearward in and by the block M.

On rearward movement of the bar E, the slot 4 therein coöperates with the stud 3 to 80 raise the upwardly reaching arm of the piece 2 into the recess of the firing pin.

The operation of my improvements will be fully understood from the foregoing, and it will also be noted that the rifle as a whole 85 is simple in construction and reliable in operation, and is well adapted to withstand the shocks and strains to which magazine rifles are ordinarily subjected.

The term "rifle" as herein employed is, 90 of course, intended to comprehend all fire arms to which my improvements are applicable.

Having described my invention, what I 95 claim and desire to secure by Letters-Pat- ent, is:

1. The combination in a rifle, of a breech frame, a hammer, a trigger having a catch, a breech block movable longitudinally in the breech frame, a longitudinally movable plunger mounted in the frame and arranged in its rear position to engage the catch of the trigger, and means movable with the block for moving the plunger in opposite directions.

2. The combination in a rifle, of a breech frame, a hammer, a trigger having a catch, a breech block movable longitudinally in the breech frame, a longitudinally movable plunger mounted in the frame and arranged in its rear position to engage the catch of the trigger, and a bar for translating the block, connected with said block and having means for moving the plunger in opposite directions.

3. The combination in a rifle, of a breech frame, a hammer, a trigger having a catch, a breech block movable longitudinally in the breech frame, a longitudinally movable plunger mounted in the frame and arranged in its rear position to engage the catch of the trigger, and a bar for translating the block, connected with said block and having a shoulder for putting the plunger in engagement with the catch when the block is 125 in its rearmost position and also having a rear extension on which is a head for disengaging the plunger from the catch when the block is closed.

4. The combination in a rifle, of a breech

- frame, a hammer, a trigger having a catch, means carried by and movable with respect to the frame, for coöperating with the catch, a breech block movable in the frame, and means movable with the block for putting the first named means in engagement with and disengaging said means from the catch. 5
5. The combination in a magazine rifle, of a breech frame, a hammer, a trigger having a catch and a finger extending forward of the catch, means carried by and movable with respect to the frame, for coöperating with the catch, a breech block movable fore and aft in the frame and adapted to move 10 the hammer and the finger rearward, and means movable with the block for putting the first named means in engagement with and disengaging said means from the catch. 15
6. The combination in a magazine rifle, 20 of a breech frame, a hammer, a trigger having a catch and a finger extending forward of the catch, a plunger movable longitudinally in the frame, for coöperating with the catch, a breech block movable fore and aft 25 in the frame and adapted to move the hammer and the finger rearward, and a bar for translating the block, connected with said block and having a shoulder for moving the plunger rearward and also having a rear 30 tension on which is a head for moving the plunger forward. 35
7. The combination in a rifle, of a breech frame, a hammer, a trigger, means carried by and movable with respect to the frame for coöperating with means of the trigger for preventing release of the hammer, a breech block movable in the frame, and means movable with the block for putting the first named means in engagement with 40 and disengaging said means from the means of the trigger. 45
8. The combination in a rifle, of a breech frame, a hammer, a trigger, means carried by and movable with respect to the frame for coöperating with means of the trigger for preventing release of the hammer, a breech block movable in the frame, means for locking the block in its closed position, and a translating bar for reciprocating the 50 block, coöperating with said locking means, and coöperating with the first named means. 55
9. The combination in a rifle, of a breech frame, a hammer, a trigger having a catch, a plunger movable longitudinally in the frame and into and out of engagement with the catch, means for locking the block in its closed position, and a translating bar for 60 moving the block, operating the locking means, and putting the plunger in engagement with and disengaging same from the catch. 65
10. The combination in a rifle, of a breech frame, a hammer, a trigger having a catch, a plunger movable longitudinally in the frame and into and out of engagement with the catch, means for locking the block in its closed position, a finger carried by and fixed to the trigger and extending forward of the catch to be engaged by the block, and a translating bar for moving the block, operating the locking means, and putting the plunger in engagement with and disengaging the same from the catch. 70
11. In a magazine rifle, a cartridge elevator equipped with a cartridge controlled 75 means held inoperative by a cartridge during elevation, and which becomes active to eject the last shell after the magazine is exhausted. 80
12. In a magazine rifle, a cartridge elevator having a spring-pressed plunger for ejecting the last shell from the rifle. 85
13. In a magazine rifle, the combination of a breech frame, a breech block movable longitudinally in the frame and having inwardly-directed flanges at its forward end, a cartridge elevator mounted in the frame and movable by the block, and a spring-backed plunger carried by the elevator, for 90 ejecting the last shell from the rifle. 95
14. The combination in a magazine rifle, of a breech frame, a magazine tube, a reciprocating breech block in which is a firing pin, a swinging piece carried by the block and coöperating with the frame and the firing pin, a swinging device controlling the exit of cartridges from the rear end of the magazine tube, a hammer, a trigger having a catch, a plunger mounted in the frame and movable into and out of engagement with 100 the catch, and a translating bar connected to the first named swinging piece and having a beveled shoulder for depressing the second named swinging piece and also having a shoulder for moving the plunger rearward and a rearward extension on which is a head for moving the plunger forward. 105
